(57) **CLAIM**

The ornamental design for a light-emitting unit, as shown and described.

DESCRIPTION

FIG. 1 is a front right perspective view of a light-emitting unit showing our new design;

FIG. 2 is a bottom perspective view of the light-emitting unit of FIG. 1;

FIG. 3 is a front view of the light-emitting unit of FIG. 1;

FIG. 4 is a rear view of the light-emitting unit of FIG. 1;

FIG. 5 is a left side view of the light-emitting unit of FIG. 1;

FIG. 6 is a right side view of the light-emitting unit of FIG. 1;

FIG. 7 is a top view of the light-emitting unit of FIG. 1;

FIG. 8 is a bottom view of the light-emitting unit of FIG. 1; and,

FIG. 9 is a rear perspective view of the light-emitting unit of FIG. 1.

The contrast in shading represents a contrast in appearance only and does not represent any particular color, material, texture or finish. The oblique shading lines in the drawings indicate a translucent material.

1 Claim, 6 Drawing Sheets
